CLAIM

The ornamental design for a fluid reservoir, as shown and
described.

DESCRIPTION

FIG. 1 is a top front isometric view of a fluid reservoir
showing the design.

FIG. 2 is a top rear isometric view of the fluid reservoir of
FIG. 1.

FIG. 3 is a bottom front isometric view of the fluid reservoir
of FIG. 1.

FIG. 4 is a bottom rear isometric view of the fluid reservoir
of FIG. 1.

FIG. 5 is a front elevation view of the fluid reservoir of FIG.
1.

FIG. 6 is a rear elevation view of the fluid reservoir of FIG.
1.

FIG. 7 is a left elevation view of the fluid reservoir of FIG.
1.

FIG. 8 is a right elevation view of the fluid reservoir of FIG.
1.

FIG. 9 is a top plan view of the fluid reservoir of FIG. 1; and,
FIG. 10 is a bottom plan view of the fluid reservoir of FIG.
1.

The dashed lines in the drawings illustrate portions of the
fluid reservoir that form no part of the claimed design. The
shading lines shown in the drawings represent the approxi-
mate three-dimensional contour of the claimed design and
are not intended to indicate surface decoration.
